UNITED STATES PATENT OFFICE

137,720

DESIGN FOR A COMBINED SOUND-RECEIVING DEVICE AND CONTROL FOR DICTATING MACHINES

Richard M. Somers, West Orange, N. J., assignor to Thomas A. Edison, Incorporated, West Orange, N. J., a corporation of New Jersey

Application September 24, 1942, Serial No. 108,330

Term of patent 14 years

(Cl. D26—14)

To all whom it may concern:

Be it known, that I, Richard M. Somers, a citizen of the United States, residing in the town of West Orange, in the county of Essex and State of New Jersey, have invented a new, original, and ornamental Design for a Combined Sound-Receiving Device and Control for Dictating Machines, of which the following is a specification, reference being had to the accompanying drawing, forming a part thereof.

In the drawing:

Fig. 1 is a perspective view of a combined sound-

receiving device and control for dictating machines showing my new design;

Fig. 2 is a front end view taken from the line 2—2 of Fig. 1; and

Fig. 3 is a side elevational view illustrating the side opposite to that shown in Fig. 1 and on a somewhat reduced scale.

I claim:

The ornamental design for a combined sound-receiving device and control for dictating machines, substantially as shown.

RICHARD M. SOMERS.
